F. E. CASE

CONTACT FINGER

Filed April 22, 1925

Inventor:
Frank E. Case,
by *Frank E. Case*
His Attorney

UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

CONTACT FINGER.

Application filed April 22, 1925. Serial No. 25,151.

This invention relates to electrical contacts, and more particularly to contact fingers for drum controllers and the like wherein the contacts are subjected to severe wear 5 from abrasion and arcing.

The present invention provides an improved form of contact which remains serviceable even after the original contact surface is worn completely through.

10 It has been heretofore proposed to form controller contact fingers of a strip of flexible metal such as steel or the like, with one end bent or crimped to form an intermediate contact surface. However, if such a contact 15 is allowed to operate too long it wears through at the point of contact, and the end breaks off with possible damage to the segments of the controller. Controller contact fingers constructed in accordance with the 20 present invention do not permit the ends of the fingers to fall off when the contact wears completely through and consequently the fingers will continue to operate satisfactorily without damage to the controller segments 25 until replaced during the periodic inspection of the controller. Thus my improved form of contact finger effectively prevents accidental interruption of service due to wearing through of the contacts and materially 30 reduces the periodic inspection and replacement ordinarily required for satisfactory service.

The invention may be carried into effect in a preferred form, as shown in the accompanying drawing, in which the single figure 35 is a perspective view of a drum controller contact finger embodying the invention, together with a cooperating controller segment.

In the drawing contact finger 10 is provided at one end with suitable holes for receiving the screws 11 and 12, which secure the finger, as well as the terminal 13, to the support 14. In the preferred form illustrated the free end of the contact finger 10 40 is bent to form an intermediate contact surface 15 having the diverging sides 16 and 17, and the end 18 of the finger 10 is looped back into engagement with the main body or stem of the finger. In order to prevent the side 17 from falling off when the contact 45 surface 15 wears through the looped back end 18 is secured to the body of the finger, preferably by welding or copper brazing.

The finger 10 is mounted so that the contact surface 15 lies in the path of movement 55 of the cooperating controller segment 19. Thus when the segment 19 is rotated into engagement with the contact finger 10 from either direction, one or the other of the diverging sides 16 and 17 is engaged by one 60 end of the segment 19 and the finger 10 yields to permit continued rotation of the segment 19. The contact surface 15 of the finger 10 is pressed into firm contacting engagement with the surface of the segment 19 65 as the latter is rotated in either direction. It will be evident that upon continued sliding of the contact surface 15 upon the segment 19 the resulting abrasion of the contact surface 15 gradually wears away the original 70 contact surface. When the contact surface 15 is completely worn through, the side 17 cannot drop off due to the fact that the end 18 is secured to the body of the finger. Thus the sides 16 and 17 are maintained in operative relation even though the original contact surface 15 is completely worn through, and no damage can result to the controller 75 through stubbing of the ends of the segment 19 against the finger 10 or through dropping of the side 17 into short circuiting relation with other contact segments of the controller.

While I have described the end 18 as welded or copper brazed to the body of the finger 10, it will be understood that the end 18 80 may be riveted or otherwise secured to the finger 10 if desired.

With my improved form of contact finger 85 wearing through of the original contact surface does not render the finger incapable of further satisfactory service and hence the finger may be continued in service until the periodic inspection discloses the worn condition of the finger so that replacement can 90 then be made.

What I claim as new and desire to secure by Letters Patent of the United States is:—

1. A contact finger comprising a metal strip having a free end bent to form an intermediate offset contact portion with diverging sides and provided with means for maintaining the said diverging sides of the offset portion in operative relation when the contact portion wears through.

2. A contact finger comprising a metal

strip having one end bent to form an intermediate offset contact surface and looped back into engagement with and secured to the body of the strip.

5. 3. A unitary contact finger comprising a flexible metal strip provided at one end with means for supporting the finger and

having the other end bent to form an offset contact surface with diverging sides and looped back into contact with an intermediate portion of the strip and secured thereto.

In witness whereof, I have hereunto set my hand this 21st day of April, 1925.

FRANK E. CASE.
